UNITED STATES PATENT OFFICE.

EARL LYONS AMES, OF SAN BERNARDINO, CALIFORNIA.

CAN-OPENER.

1,094,384.

Specification of Letters Patent.

Patented Apr. 21, 1914.

Application filed July 17, 1913. Serial No. 779,597.

To all whom it may concern:

Be it known that I, EARL L. AMES, a citizen of the United States, residing at San Bernardino, in the county of San Bernardino and State of California, have invented certain new and useful Improvements in Can-Openers; and I do hereby declare the following to be a full, clear, and exact description of the invention, such as will enable others skilled in the art to which it appertains to make and use the same.

My invention relates to new and useful improvements in can openers and has particular reference to that type which are adapted to punch openings in the tops of cans, such as condensed or evaporated milk cans or any other cans having contents of such nature as to require small openings only to provide for the removal of the contents of a can.

An important object of my invention is to provide a device of the above mentioned character consisting of pivoted jaws, one of which is arranged to engage the rim of a can, the other of which is provided with a sharpened point adapted to punch an opening in the can.

A further important object of my invention is to provide a device of the above mentioned character constructed of few parts, reliable in its operation, and cheap to manufacture.

The above and additional objects are accomplished by such means as are illustrated in the accompanying drawings, described in the following specification, and then more particularly pointed out in the claim which is appended hereto and forms a part of this application.

With reference to the drawings, wherein I have illustrated the preferred embodiment of my invention as it is reduced to practice, and throughout the several views of which similar reference numerals designate corresponding parts: Figure 1 is a side elevation of my can opener in its operative position showing the upper corner of the can in section. Fig. 2 is a top plan view of the pivoted jaws of my can opener, and Fig. 3 is a perspective view of the jaws showing the spaced relationship thereof.

Referring now to the drawing, the numerals 1 and 2 designate crossed handles that are pivotally connected in any desired way, as indicated at 3'. Each of the pivoted handles 1 and 2 are provided terminally with finger engaging portions 3 and 4 similar to the type employed in connection with scissors or shears. Forwardly of the pivot 3' the handles 1 and 2 comprise jaws 5 and 6. The jaw 5 is curved, as shown, and projects beyond the extremity of the jaw 6. The end of the jaw 5 is reduced to provide a punch 7 having a sharpened point 8. The jaw 6 is curved toward the jaw 5 and is engaged, as indicated at 8, and provided at its extremity with a beveled face 9 which is adapted to engage the rim 10 formed on the upper portion of a can, designated as an entirety by the numeral 11, during the operation of 70 punching a hole in the top of the can.

In operation, the beveled face 9 of the enlarged portion 8 on the jaw 6 is placed into engagement with the rim 10 of the can 11 and the handles 1 and 2 are operated so as 75 to cause the jaw 5, having the punch 7 formed thereon and provided with a sharpened point 8, to be inserted through the top of the can and thereby form an opening.

It is apparent with reference to the drawing and description that a device is provided which is adapted to accomplish all the functions that are herein recited.

In reduction to practice, I have found that the form of my invention, illustrated 85 in the drawings and referred to in the above description, as the preferred embodiment, is the most efficient and practical; yet, realizing that the conditions concurrent with the adoption of my device will necessarily vary, 90 I desire to emphasize the fact that various minor changes in details of construction, proportion and arrangement of parts may be resorted to, when required, without sacrificing any of the advantages of my invention, as defined in the appended claim.

Having thus fully described my invention, what I claim is:

A can opener comprising a pair of pivot-ed crossed handles, one of said handles being extended forwardly of the pivot and reduced to provide a prong, said prong being

tapered to a point and disposed approximately at right angles to the handle, and the other of said handles being extended forwardly of the pivot and disposed at approximately right angles to the handles, said last named right angular portion being flattened, and chamfered at its free edge, said chamfered edge disposed transversely

of the handles and being disposed in spaced relation to said prong inwardly thereof.

10

In testimony whereof I affix my signature in presence of two witnesses.

EARL LYONS AMES
